UNITED STATES PATENT OFFICE

JARED BARTON FLEMING, OF TOWSON, MARYLAND, ASSIGNOR TO THE BLACK & DECKER MANUFACTURING COMPANY, OF TOWSON, MARYLAND, A CORPORATION OF MARYLAND

DESIGN FOR A PORTABLE FENDER STRAIGHTENING TOOL FRAME

Application filed May 1, 1931. Serial No. 39,682. Term of patent 7 years.

To all whom it may concern:

Be it known that I, JARED BARTON FLEMING, a citizen of the United States of America, residing at Towson, Baltimore County, Maryland, have invented a new, original, and ornamental Design for a Portable Fender Straightening Tool Frame, of which the following is a specification, reference being had to the accompanying drawing, forming part thereof.

In the drawing:

Figure 1 is a perspective view of the tool frame looking from the side slightly back of the center.

Figure 2 is a perspective looking from the front quarter.

I claim:

The ornamental design for a portable fender straightening tool frame as shown.

Signed by me at Towson, Baltimore County, Maryland, this 27th day of April, 1931.

JARED BARTON FLEMING.
